FUEL DISTRIBUTING APPARATUS

Nathan M. Lower, Tuckahoe, N. Y., assignor, by
mesne assignments, to The Standard Stoker
Company, Inc., (1922), New York, N. Y., a cor-
poration of Delaware

Original application February 13, 1929, Serial No.
339,544. Divided and this application Decem-
ber 20, 1933, Serial No. 703,197

16 Claims. (Cl. 110—101)

This invention relates to a fuel distributing apparatus for fireboxes to be used in connection with mechanical stokers and is the result of much experimenting to provide a means for distributing both large and fine coal uniformly over the grates to maintain a level fire. The provision of such means is the main object of this invention.

Other objects of the invention will be apparent during the course of the following description taken in connection with the accompanying drawing, in which

Fig. 1 is a vertical sectional view of the fuel distributing apparatus projecting in the firing opening of a locomotive firebox.

Fig. 2 is a part sectional view taken on line 2—2 of Figure 1.

Fig. 3 is a front end view of the fuel distributing apparatus.

Fig. 4 is a plan view of the jet casting.

Fig. 5 is a vertical sectional view through the jet openings of the fuel distributing apparatus and illustrates the method of discharging large and fine coal.

Fig. 6 is a vertical sectional view taken on line 6—6 of Figure 4.

Similar reference characters in the following description designate corresponding parts in the several figures of the drawing.

The numeral 1 designates the backhead of a locomotive boiler with the firing opening 2 through which the fuel is supplied to the firebox by hand or by stoker 3.

Arranged within the firing opening 2 is the fuel distributing apparatus, designated as a whole by the numeral 4. This apparatus is supported on the bottom of the firing opening 2 by the special stud 5 and is secured to the stoker fuel conduit 3 by the hook-bolt 6. The fuel distributing apparatus 4 comprises the jet member or casting 7 and the distributor plate or table 8. The jet member 7 is provided with a top wall 40, constituting a support for the fuel as it is conveyed through the stoker conduit 3 by a conveyor screw 41. This wall 40 terminates in a forward edge 42 which is spaced a substantial distance above the surface 43 of the distributor table 8, which surface forms the sole support for all the fuel which has passed over the edge 42. By this construction, the fuel upon passing over the edge 42 drops in an unsupported stream a substantial distance toward the fuel supporting surface 43 of the table 8. Because of this unsupported drop, closely adhering fuel lumps or particles become dispersed, in which

state they are more efficiently distributed over the firebed by the action of pressure fluid jets, to be hereinafter described. These jets of pressure fluid aid in dispersing the fuel since they are arranged to project some of the fuel before it falls onto the table 8 but only after it has passed over the edge 42. At the lower portion of the forward end of the jet casting 7 is the forwardly extending flange 9. The table 8 is secured to the top of the flange 9 by the screws 10. The tops of the screws 10 are made to come flush with the top surface of the table 8 to provide a smooth surface over which the fuel is discharged by the jets at the forward end of the jet casting 7.

It has been found that the present steam jet fuel distributing apparatus in which a single horizontal row of jets is provided to discharge the fuel into the firebox does not distribute evenly over the grate. This is because the pressure of the jets can not be regulated to suit the various sizes of fuel that fall before them. A small lump will be blown to the front of the grates while a large lump will not be blown nearly so far. By referring to Figure 5 of the drawing it will be seen that I have overcome this disadvantage by providing an upper horizontal row 11 and a lower horizontal row 12 of jet openings which are formed in the front wall 30 of the jet member 7. The blasts of pressure fluid issuing from the jet openings 11, 12 are the sole means for projecting the fuel over the firebed and a sufficient number of these jets is made possible by reason of the fact that the front wall or face 30 is of a height sufficient to assure the desired drop for the fuel passing over the edge 42. The small lumps of fuel will be discharged by a single jet while the large lumps will be discharged by a plurality of jets. The upper row of jet openings 11 are in communication with the cored chamber 13 and the lower row of jet openings 12 are in communication with the cored chamber 14. The two chambers 13 and 14 are separated from each other by the horizontal partition 15. On each side of the double row of jet openings is a single row 16 and 17 drilled in the angular faces 16a and 17a respectively for discharging the fuel to the rear portion of the sides and the rear corners of the firebox. The side portions 31, 32 of the plate 8 are sloped downwardly from the straight central portion 33 to facilitate the discharge of coal to the rear corners of the firebox. The side rows of jet openings 16 and 17 are in communication with the cored lateral chambers 18 and 19 respective-

ly. The cored chambers 13, 14, 18, and 19 extend to the rear of the jet casting 7 and have pipe lines 20, 21, 22, and 23 respectively leading to a supply of steam pressure. Inserted in the pipe lines are suitable valves 35 for controlling the pressure of the upper row 11, the lower row 12, and the side row 16 and 17 of jet openings independently of each other; which gives the fireman additional control of the fuel distribution.

As a further control of fuel distribution, deflector vanes 44, 45 are provided, one at each side of the delivery end of the stoker conduit. Each vane is pivotally mounted at its rearward end whereby the forward end thereof may be set to intersect the respective angular faces 16a, 17a, in different positions. Thus, as illustrated in Figure 2, the vane 44 is set in such relation with the angular face 16a that more fuel falls in front of the jet openings 16, than in front of the jet openings 17 in angular face 17a it being apparent that the setting of the vane 45 is nearer to the axis of the conduit than the setting of the vane 44.

25 The jet openings are drilled at various angles so that each jet will supply a particular area of the grate. For aiding in directing the fuel to the particular area to which it is to be discharged I have provided the radial forwardly diverging ribs 24 on the table 8. These ribs 24 are preferably positioned centrally between the jet openings in the lower row 12 and below the level of the upper row of jet openings 11. They can either be made separately and secured to the table 8 or be cast integral with the table 8.

I have illustrated this invention in connection with a stoker having a screw delivering to the firing opening of the firebox but it should be understood that any type of stoker conveying means can be combined with this invention, and I do not limit myself just to the combination illustrated.

This application is a division of my application, Serial No. 339,544, filed February 13, 1929, 45 for Fuel distributing apparatus, which application issued December 3, 1935, as United States Letters Patent 2,022,966.

I claim:

1. In a fuel distributing apparatus, the combination with a boiler firebox having a backhead with a firing opening therein and a stoker conduit in communication with said opening, of a jet member at the lower edge of the discharge end of said conduit, said jet member being horizontally divided into a plurality of chambers, each chamber having a horizontal row of radiating jet openings directed forward, means for supplying fluid under pressure to said chambers, means for independently controlling the pressure of the fluid in said chambers, a distributor plate immediately forward of said jet openings and slightly below the same, and laterally spaced radiating ribs on the upper surface of said plate forming longitudinally extending channels, said jet member and said distributor plate arranged with the channels of the plate positioned in substantially the same forwardly extending vertical planes as the jet openings of the lower row.

2. In a fuel distributing apparatus, the combination with a boiler firebox having a backhead with a firing opening therein and a stoker conduit in communication with said opening, of a jet member at the lower edge of the discharge end of said conduit, said jet member being horizontally divided into a plurality of chambers, each chamber having a horizontal row of radiating jet openings directed forward and located forward of the inside sheet of the backhead, means for supplying fluid under pressure to said chambers, means for independently controlling the pressure of the fluid in said chambers, a distributor plate immediately forward of said jet openings and slightly below the same, and laterally spaced radiating ribs on the upper surface of said plate forming longitudinally extending channels, said jet member and said distributor plate arranged with the channels of the plate positioned in substantially the same forwardly extending vertical planes as the jet openings of the lower row.

3. In a fuel distributing apparatus, the combination with a boiler firebox having a backhead with a firing opening therein and a stoker conduit in communication with said opening, of a jet member at the lower edge of the discharge end of said conduit, two parallel horizontal rows of jet openings in the central portion of the forward end of said jet member, a single row of jet openings at each side of said double row, means for supplying fluid under pressure to the jet openings, means for independently controlling the pressure of the fluid in each of the central rows of jet openings and each of the side rows of jet openings, a distributor plate immediately forward of said jet openings and slightly below the same, and laterally spaced radiating ribs on the upper surface of said plate forming longitudinally extending channels, said jet member and said distributor plate arranged with the channels of the plate positioned in substantially the same forwardly extending vertical planes as the jet openings of the lower row.

4. In a fuel distributing apparatus, the combination with a boiler firebox having a backhead with a firing opening therein and a stoker conduit in communication with said opening, a jet member at the lower edge of the discharge end of said conduit, said jet member being horizontally divided into a plurality of chambers, each chamber having a horizontal row of radiating jet openings, the jet openings in the top row being in vertical alignment with the jet openings in the bottom row, means for supplying fluid under pressure to said chambers, means for independently controlling the pressure of the fluid in said chambers, a distributor plate immediately forward of said jet openings and slightly below the same, and laterally spaced radiating ribs on the upper surface of said plate forming longitudinally extending channels, said jet member and said distributor plate arranged with the channels of the plate positioned in substantially the same forwardly extending vertical planes as the jet openings of the lower row.

5. In a fuel distributing apparatus, the combination with a boiler firebox having a backhead with a firing opening therein and a stoker conduit in communication with said opening, of a jet member at the lower edge of the discharge end of said conduit, said jet member being horizontally divided into a plurality of chambers, each chamber having a horizontal row of radiating jet openings directed forward and located forward of the inside sheet of the backhead, means for supplying fluid under pressure to said chambers, means for independently controlling the pressure of the fluid in said chambers, a distributor plate immediately forward of said jet openings and slightly below the same, and laterally spaced radiating ribs on the upper surface of said plate forming longitudinally extending channels, said jet member and said distributor plate arranged with the channels of the plate positioned in substantially the same forwardly extending vertical planes as the jet openings of the lower row.

6. In a fuel distributing apparatus, the combination with a boiler firebox having a backhead with a firing opening therein and a stoker conduit in communication with said opening, of a jet member at the lower edge of the discharge end of said conduit, said jet member being horizontally divided into a plurality of chambers, each chamber having a horizontal row of radiating jet openings directed forward and located forward of the inside sheet of the backhead, means for supplying fluid under pressure to said chambers, means for independently controlling the pressure of the fluid in said chambers, a distributor plate immediately forward of said jet openings and slightly below the same, and laterally spaced radiating ribs on the upper surface of said plate forming longitudinally extending channels, said jet member and said distributor plate arranged with the channels of the plate positioned in substantially the same forwardly extending vertical planes as the jet openings of the lower row.

of said plate forming longitudinally extending channels, said jet member and said distributor plate arranged with the channels of the plate positioned in substantially the same forwardly extending vertical planes as the jet openings of the lower row. 5

6. In combination, a boiler firebox having a backhead with a firing opening therein, a stoker conduit in communication with said opening, a 10 jet member at the lower edge of the discharge end of the conduit, said jet member being divided into a plurality of chambers, at their discharge ends disposed vertically with respect to each other, each of said chambers receiving 15 pressure fluid at a point rearward of said firebox and externally of said stoker conduit, each chamber extending into the firebox through said firing opening and having a horizontal row of radiating jet openings directed forward from 20 the front face thereof, means for independently controlling the fluid pressure in each of said chambers, a distributor plate extending forwardly into the firebox from a point below said jet openings, and laterally spaced radiating ribs on 25 the upper surface of said plate forming longitudinally extending channels, said jet member and said distributor plate arranged with the channels of the plate positioned in substantially the same forwardly extending vertical planes as the 30 jet openings of the lower row.

7. In combination, a boiler firebox having a backhead and a firing opening therein, a stoker conduit in communication with said opening and including a separable jet member at the discharge end thereof, said jet member being horizontally divided into a plurality of chambers, each chamber having a horizontal row of radiating jet openings directed forward, means for supplying pressure fluid to said chambers, means 35 for independently controlling the pressure of the fluid in said chambers, a distributor plate separable from and secured to said jet member disposed immediately forward of said jet openings and slightly below the same, and laterally spaced radiating ribs on the upper surface of 40 said plate forming longitudinally extending channels, said jet member and said distributor plate arranged with the channels of the plate positioned in substantially the same forwardly extending vertical planes as the jet openings of 45 the lower row.

8. A fuel distributor for stokers comprising a jet member including an upstanding wall and having a plurality of internal chambers disposed 50 vertically with respect to each other, each chamber being arranged to receive pressure fluid and having a horizontal row of radiating jet openings directed through the named upstanding wall of said member, and a distributor plate extending 55 forward from said wall and disposed in a substantially horizontal plane below said jet openings, the upper surface of said plate being provided with laterally spaced radiating ribs forming longitudinally extending channels, said jet member and said distributor plate arranged 60 with the channels of the plate positioned in substantially the same forwardly extending vertical planes as the jet openings of the lower row.

9. A fuel distributor for stokers comprising a jet member including an upstanding wall provided with a plurality of horizontal rows of jet openings therethrough, said member having internal chambers arranged to receive pressure fluid communicating with said jet openings for the discharge of pressure fluid therethrough, and 70 a distributor plate detachably connected to said member, said plate being supported from said member and having one side in contact with the named wall of said jet member, the upper surface of said plate being provided with laterally spaced ribs forming longitudinally extending channels, said jet member and said distributor plate arranged with the channels of the plate positioned in substantially the same forwardly extending vertical planes as the jet openings of the lower row. 75

10. In combination, a stoker conduit, a chambered jet member at the delivery end of said conduit including an upstanding wall extending transversely thereof and having a central portion and side portions facing outwardly and disposed angularly with respect to the central portion, a distributor plate extending forwardly from said jet member, said plate having a substantially horizontally disposed central portion immediately forward of the central portion of said upstanding wall and downwardly sloping side portions adjacent said side portions of the upstanding wall, the latter having a plurality of jet openings in its central portion directed over the central portion of said plate and at least one jet opening in each side portion directed over a respective sloping side portion of said plate. 20

11. In combination, a stoker conduit, a chambered jet member at the delivery end of said conduit including an upstanding wall extending transversely thereof and having a central portion and side portions facing outwardly and disposed angularly with respect to the central portion, a distributor plate extending forwardly from said jet member, said plate having a substantially horizontally disposed central portion immediately forward of the central portion of said upstanding wall and downwardly sloping side portions adjacent said side portions of the upstanding wall, the latter having a plurality of jet openings in its central portion arranged in a plurality of parallel rows and in vertical alignment directed over the central portion of said plate and at least one jet opening in each side portion directed over a respective sloping side portion of said plate. 30

12. In combination, a stoker conduit, a chambered jet member at the delivery end of said conduit including an upstanding wall extending transversely thereof and having a central portion and side portions facing outwardly and disposed angularly with respect to the central portion, and a distributor plate extending forwardly from said jet member, said plate having a substantially horizontally disposed central portion immediately forward of the central portion of said upstanding wall and side portions adjacent said side portions of the upstanding wall, the latter having a plurality of jet openings in its central portion directed over the central portion of said plate and at least one jet opening in each side portion directed over a respective side portion of said plate, said plate having an upstanding fuel deflecting surface at each end thereof interposed between the jets discharging from the centrally disposed jet openings and the jets discharging from the side jet openings. 50

13. In combination, a stoker conduit, a chambered jet member at the delivery end of said conduit including an upstanding wall extending transversely thereof and having a central portion and side portions facing outwardly and disposed angularly with respect to the central portion, a distributor plate extending forwardly 60

70

from said jet member, said plate having a substantially horizontally disposed central portion immediately forward of the central portion of said upstanding wall and downwardly sloping side portions adjacent said side portions of the upstanding wall, the latter having a plurality of jet openings in its central portion arranged in a plurality of parallel rows, the openings of different rows being in the same vertical planes directed over the central portion of said plate and at least one jet opening in each side portion directed over a respective sloping side portion of said plate, and an upstanding rib at each end of said plate interposed between the jets discharging from the centrally disposed jet openings and the jets discharging from the side jet openings.

14. As a new article of manufacture, a distributor jet member for a stoker including in operative position an upstanding transversely extending wall of greater width than height, said upstanding wall including a central portion and end portions, each of said end portions standing in a plane angularly related with respect to the plane of said central portion, an approximately flat plate-like member joining the contiguous top edges of the central and end portions of said upstanding wall, a wall spaced beneath said plate-like member, and a plurality of partition walls in the space included between said last named wall and said flat plate-like member, and between the central and end portions of said upstanding wall defining chambers spaced one above the other and disposed at said upstanding wall centrally between the ends thereof, and a pair of spaced side chambers disposed one at each side of the aforesaid centrally disposed chambers, each side chamber being positioned adjacent a respective end portion of said upstanding wall, the latter having jet openings in its central portion communicating with said centrally disposed chambers and at least one jet opening in each end portion communicating with a respective side chamber, the jet openings in the central portion of said upstanding wall including plurally grouped jet openings divided into upper and lower rows, each group communicating with a respective chamber, the jet openings in the upper and lower rows being in approximate vertical alignment, each of said chambers having an inlet opening adjacent the end of

said flat plate-like member remote from said upstanding wall.

15. In combination, a stoker conduit, a distributor jet member at the delivery end of said conduit including an upstanding wall extending transversely thereof and having a central portion and side portions facing outwardly and disposed angularly with respect to the central portion, said jet member being provided with a plurality of vertically spaced chambers at the said upstanding wall and a chamber at each side portion, a distributor plate extending forwardly from the central and side portions of said upstanding wall, the latter having laterally spaced groups of jet openings in its central portion directed over the central portion of said distributor plate and at least one jet opening in each side portion communicating with a respective chamber at such side portion and being directed over a respective side portion of said distributor plate, the jet openings in the central portion of said upstanding wall including plurally grouped jet openings divided into upper and lower rows, each group communicating with a respective chamber at said upstanding wall, the jet openings in the upper and lower rows being in approximate vertical alignment, and means for supplying pressure fluid to said chambers.

16. In combination, a stoker conduit, a distributor jet member at the delivery end of said conduit including an upstanding wall extending transversely thereof, a distributor plate extending forwardly from said upstanding wall, said jet member being provided with a plurality of vertically spaced chambers at the upstanding wall and located between the ends of said upstanding wall and a chamber at each side of said first-mentioned chambers, said upstanding wall being provided between its ends with plurally grouped jet openings divided into upper and lower rows, each group communicating with a respective centrally located chamber, the jet openings in the upper and lower rows being in approximate vertical alignment, said upstanding wall being provided with a jet communicating with each of said side chambers, said jets being disposed at an oblique angle with respect to the median line of said jet member, and means for supplying pressure fluid to said chambers.

NATHAN M. LOWER.
